UNITED STATES PATENT OFFICE.

WILLIAM HEINMILLER, OF CHESLEY, ONTARIO, CANADA.

SUSPENDERS.

1,073,604.

Specification of Letters Patent.

Patented Sept. 23, 1913.

Application filed January 16, 1913. Serial No. 742,315.

To all whom it may concern:

Be it known that I, WILLIAM HEINMILLER, of the town of Chesley, county of Bruce, Province of Ontario, Canada, have 5 invented certain new and useful Improvements in Suspenders, of which the following is a specification.

My invention relates to improvements in suspenders, and relates more particularly 10 to that class of suspenders known as "invisible" suspenders and which are worn under the shirt. All suspenders of this class with which I am acquainted, when the same are disconnected from the trousers, slip up 15 under the shirt, and it requires considerable patience on the part of the wearer to find the connecting ends of the brace and couple them again to the trousers.

Now the principal object of my invention 20 is to design the supporting ends of my suspenders so that there will be no difficulty in finding the ends of the suspenders when coupling the same again to the buttons.

Another object of my invention is to design 25 a coupling element of a particular construction which coupling element will be coupled to the ends of the braces, and positioned outside of the shirt so that the braces may be readily coupled to and uncoupled 30 from the buttons of the trousers, and the invention, broadly considered, comprises a coupling element composed of inner and outer plates, spaced apart, each of which is provided with a single opening, the opening 35 in the outer plate being designed to couple and uncouple the coupling element to and from the buttons of the trousers, and the opening in the inner plate being designed to couple the coupling element to a 40 stud carried by each end of the braces, and means carried by said coupling element whereby said stud is prevented from accidental disengagement from said coupling element, as hereinafter more particularly 45 set forth.

Figure 1 is a vertical central section through my coupling element, showing the preferred construction thereof, and showing one end of the braces, in side elevation, 50 coupled thereto, these elements being shown attached to the shirt and to the trousers, portions of which garments are shown in section. Figs. 2 and 3 are perspective views of my preferred form of coupling element, 55 looking at different sides, and Fig. 4 is a perspective view of the preferred form of

construction of the lower end of the braces used with my coupling element.

In the drawings, like characters of reference indicate corresponding parts in each 60 figure.

My preferred form of coupling element A is composed of outer and inner plates B and C, preferably integrally formed from a single piece of suitable material, preferably steel of a light gage. The said plates are spaced apart as shown, and are braced together at their upper ends by any suitable means. My preferred means for this purpose comprises ears D which are 65 integrally formed preferably with the outer plate B. These ears are shaped substantially as shown in Figs. 2 and 3 and are brazed or otherwise suitably secured to the upper portions of the inner plate C. Formed in the outer plate B is an opening E. 70

F is a slot formed in the upper portion of the outer plate B and opening into the upper portion of the opening E.

When the coupling element is in use, the same is connected to the trousers G by placing the slot F underneath the button H and moving the coupling element A upward until the thread I connecting the button to the trousers is positioned in the opening E. Each end J of the braces is suitably provided with a plate K in which is mounted a stud L, the head M of which is positioned the desired distance beyond the plate 80 K. Formed in the inner plate C is an opening N substantially circular in shape, and connected with this opening at the upper side thereof is a slot O. Before the coupling element A is coupled to the trousers, it is 85 placed so that the inner plate C thereof will rest against the shirt 20. The head M of the stud L, which is suspended by the braces and positioned underneath the shirt, is then passed through the opening N, carrying a portion of the shirt with it, and the stud L is moved until it occupies the slot 90 O and rests against the top thereof.

Integrally formed with the inner plate C is a tongue P which is positioned between 105 the two plates B and C, and behind the slot O and in part behind the opening N. This tongue is sufficiently resilient and presses against the portion of the shirt held within the coupling element, and the head M, and so prevents the accidental uncoupling of the 110 stud L from the coupling element A.

In order to uncouple the coupling element A from the trousers C it is only necessary to shove the coupling element A downward so as to escape the button H. The 5 coupling element will of course fly upward with the ends of the braces and the shirt, but it will be apparent to one skilled in this art that there will be no difficulty in locating the said coupling element when it is 10 desired to again couple the same to the trousers.

The tongue B is provided with an off-set portion R thus forming a flange which retains the stud L snugly in place. Integrally 15 formed with the off-set portion R is a lip Q which acts as a guard to prevent the flange of the head M from catching underneath the off-set portion R when coupling the stud to the coupling element.

20 The upper portion of the inner plate C is provided with a flange T, which, together with the upper end of the tongue P forms a pocket U into which extend a portion of the shirt and the upper flange V of the 25 head M.

Upon referring particularly to Fig. 2, it will be noticed that the upper portion of the slot F is wider than the lower portion, thus providing a construction whereby the 30 thread I or attaching means for the button H can readily be passed into the opening E.

The sides of the openings E and N and slots F and O are flanged as shown at a to remove all sharp edges at these places to 35 prevent the coupling elements cutting or tearing the garments.

While I have described what I consider to be the best embodiment of my invention, I desire it to be understood that the principles 40 can be embodied in different forms and I desire not to be limited beyond the requirements of the prior art, and the terms of my claims.

What I claim as my invention is:

45 1. As a new article of manufacture, a coupling element for suspenders integrally formed from a single piece of sheet metal and comprising inner and outer plates spaced apart and integrally connected together at their lower ends, the said outer plate being provided with an opening into which opens a flared slot formed in the top of said plate, a tongue integrally formed with an upper flange formed near the top of said 50 inner plate, the upper end of said tongue being spaced apart from said flange to form

a pocket, the said pocket communicating with an opening formed through said inner plate, and behind which said tongue extends, the said opening designed to receive the 60 head of a stud, a portion of which rests in said slot, and means bracing said plates together to hold them in relationship.

2. As a new article of manufacture, a coupling element for suspenders, integrally 65 formed from a single piece of sheet metal and comprising inner and outer plates spaced apart and integrally connected together at their lower ends, the said outer plate being provided with an opening into 70 which opens a flared slot formed in the top of said plate; a tongue integrally formed with an upper flange formed near the top of said inner plate, the upper end of said tongue being spaced apart from said flange 75 to form a pocket, the said pocket communicating with an opening formed through said inner plate, and behind which said tongue extends, the said opening designed to receive the 80 head of a stud, a portion of which rests in said slot; an offset lower portion forming part of said tongue and positioned in said opening, and means bracing said plates together to hold them in relationship.

3. As a new article of manufacture, a 85 coupling element for suspenders, integrally formed from a single piece of sheet metal, and comprising inner and outer plates spaced apart and integrally connected together at their lower ends, the said outer 90 plate being provided with an opening into which opens a flared slot formed in the top of said plate; a tongue integrally formed with an upper flange formed near the top of said inner plate, the upper end of said tongue 95 being spaced apart from said flange to form a pocket, the said pocket communicating with an opening through said inner plate, and behind which said tongue extends, the said opening designed to receive the 100 head of a stud, a portion of which rests in said slot; an offset lower portion forming part of said tongue and positioned in said opening, and a pair of ears integrally formed with said inner plate and one at each side 105 thereof and extending backward and suitably secured to said upper plate, thereby bracing said plates together, as set forth.

WILLIAM HEINMILLER.
